UNITED STATES PATENT OFFICE

116,557

DESIGN FOR A DISPLAY CASE

Ernest R. Erickson, Des Moines, Iowa, assignor to C. E. Erickson Company, Incorporated, Des Moines, Iowa, a corporation of Iowa

Application February 27, 1939, Serial No. 83,236

Term of patent 7 years

To all whom it may concern:

Be it known that I, Ernest R. Erickson, a citizen of the United States and a resident of Des Moines, in the county of Polk and State of Iowa, have invented a new, original, and ornamental Design for a Display Case, of which the following is a specification, reference being had to the accompanying drawing, forming part thereof.

The rear of the display case is identical with the front.

I claim:

The ornamental design for a display case, substantially as shown and described.

ERNEST R. ERICKSON.
